UNITED STATES PATENT OFFICE.

HENRY TEXTOR, OF BROOKLYN, NEW YORK, ASSIGNOR TO JAMES S. SIMPSON AND GEORGE F. SIMPSON, BOTH OF SAME PLACE.

DESIGN FOR A NEWEL-POST.

SPECIFICATION forming part of Design No. 14,986, dated April 29, 1884.

Application filed January 3, 1884. Term of patent 7 years.

To all whom it may concern:

Be it known that I, HENRY TEXTOR, of Brooklyn, in the county of Kings and State of New York, have invented and produced a new Design for Newel-Posts, of which the following is a specification.

I will describe in detail a newel-post embodying my design, and then point out the various features in claims.

10 The accompanying illustration is a perspective view of a newel-post embodying my design.

The base *a* of the newel is polygonal. It is embellished with a convex molding, *b*, and a 15 surmounting concave molding, *c*. Above the moldings *e* are moldings *d e f*. The body of this newel is polygonal, and tapers upward. Near the lower end is a band-like molding, *g*, which comprises on the several sides of the body circular portions *g'*, embellished with rosettes *g''*. On the sides of the body are panels *h*, ornamented around the edges with moldings *h'*, and containing tablets *h''*. The lower part of the moldings *h'* and tablets *h''* is curved to conform to the circular portions *g'* of the band-like molding *g*. The upper part of the body is surrounded with moldings *i j*, between which is a portion, *k*, having a plane surface. Between the moldings *g* and *i* the corners of the body are chamfered off, and are embellished with diamond-shaped ornaments *l*. Above the moldings *j* is a portion, *m*, ornamented by scallops *n*. A convex molding, *o*, is arranged above the portion *m*, and a flat angular molding, *p*, surmounts the

molding *m*. Above the molding *p* is a flat-sided portion, *q*. The newel has a finial, which, at the base, has a flat-sided portion, *r*. Above the portion *r* is a concave portion, *s*, surmounted by a cylindric portion, *t*, having 40 vertical flutes. Above the flutes there is a band-like portion, *u*. Surmounting the band-like portion *u* is a concave portion, *v*, which extends outward at the top. On the cylindric portion *t* of the finial are leaf-shaped ornaments *x*, with the points turned upward.

What I claim as my design, and desire to secure by Letters Patent, is—

1. In a design for a newel-post, the body thereof having the base *a*, the convex molding *b*, the concave molding *c*, and the moldings *d e f*, the band-like molding *g*, having portions *g'* and rosettes *g''*, panels *h*, ornamented with moldings *h'* and containing tablets *h''*, the moldings *i j*, the portion *k*, diamond-shaped ornaments *l*, the portion *m*, having scallops *n*, convex moldings *o*, moldings *p*, and the portion *q*, as shown. 50

2. In a design for a newel-post, the body thereof having band-like moldings *g*, circular portions *g'*, rosettes *g''*, panels *h*, moldings *h'*, tablets *h''*, moldings *i* and *j*, the portion *k*, diamond-shaped ornaments *l*, the portion *m*, scallops *n*, the convex molding *o*, the molding *p*, and the flat-sided portion *q*, as shown. 55
